CLAIM

The ornamental design for a hairbrush handle, as shown and described.

DESCRIPTION

FIG. 1 is a top perspective view of the hairbrush handle, showing my new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof; and,

FIG. 8 is a front perspective view thereof.

The dash-dash broken lines shown in the drawings illustrate portions of the article, and form no part of the claimed design. The dot-dash broken lines shown in FIGS. 1-5 and 8 are for the purpose of illustrating a boundary line, and form no part of the claimed design.

1 Claim, 7 Drawing Sheets
